UNITED STATES PATENT OFFICE.

HATTIE MYRA WALSH, OF SAN FRANCISCO, CALIFORNIA.

BLOOMERS.

1,426,525.

Specification of Letters Patent. Patented Aug. 22, 1922.

Application filed April 6, 1921. Serial No. 458,952.

To all whom it may concern:

Be it known that I, HATTIE MYRA WALSH, a citizen of the United States, residing in the city and county of San Francisco and State of California, have invented a new and useful Improvement in Bloomers, of which the following is a specification.

My invention relates to improvements in bloomers wherein a crotch opening operates in conjunction with a protective strip to provide comfort, accessibility and protection to a wearer.

The primary object of the present invention is to provide new and improved under-garment for women.

A further object of the invention is to provide new and improved bloomers having a crotch opening to provide accessibility for evacuation purposes, and improved means for covering said crotch to protect the inter-gluteal fold of a wearer.

A further object is to provide an improved bloomer having a sanitary protective strip, the intermediate or contacting portion of which is separable from the garment whereby the same may be rendered accessible for cleansing purposes without washing the entire garment.

I accomplish these and other objects by means of the improved garment disclosed in the drawings forming a part of the present specification, wherein like characters of reference are used to designate similar parts throughout the said specification and drawings, and in which—

Fig. 1 is a front elevation of my improved under-garment, partly broken away to disclose the construction thereof; and

Fig. 2 is a vertical sectional view of the garment as draped upon the person.

Referring to the drawings the numeral 1 is used to designate in general a pair of bloomers or undergarment having a crotch opening 2 which extends, when the garment is draped upon the person, substantially from the perineum to the sacrum, said crotch opening 2 having edges 3.

A strip 4 has its ends only secured to the front and back of the bloomers 1 and adjacent the ends of the crotch opening 2 and is arranged to cover said opening and is further provided with laterally disposed tapes 6 arranged to impart sufficient rigidity transversely of said strip 4 to tend to prevent the formation and entrance of longi-

tudinal folds or creases into the inter-gluteal fold of a wearer, the purpose of which will hereinafter be more fully set forth.

The garment or bloomers 1 are provided with elastic upper and lower edges 7 and 8 respectively, said upper elastic edge 7 being provided with an opening 9 in the back thereof, the portions or corners of said upper edge 7 adjacent said opening 9, being provided with suitable fastening means, preferably a hook and eye 11, as disclosed in Fig. 1 of the drawings.

In practice, the opening 9 permits passage of the upper elastic edge 7 over the hips of a wearer, during removal and replacement of the garment, without exposing the elastic edge 7 to undue stresses and strains.

The crotch opening 2 provides accessibility for evacuation purposes without lowering the garment 1 and thereby stretching the upper elastic edge 7. To protect the intergluteal fold of a wearer from exposure and at the same time prevent the edges 3 of the crotch opening 2 from entering the said fold, the strip 4 is provided. The tapes or other stiffening elements 6 are provided laterally to prevent the formation and entrance of longitudinal creases or folds into said inter-gluteal fold thereby providing sanitation of said edges and comfort to the wearer.

The crotch opening 2 also permits a ready adjustment of the material of the garment and prevents stretching of the same across the seat when the wearer is in a sitting posture, thereby preventing undue wear of the seat of the garment, while the strip 4 covers the said crotch opening during such posture to prevent exposure, and contact of the said garment with said inter-gluteal fold.

The strip 4 may also be used to retain in position a sanitary napkin when required, thereby preventing soiling of the garment and eliminating the necessity of a belt and other straps for holding said napkin in position.

The strip 4 being unattached intermediate its secured ends, said intermediate portion, which contacts with said inter-gluteal fold, may be readily isolated from other portions of the garment and washed daily and independently of said garment and without moistening the rest of said garment.

The intermediate detached portion of the strip 4 may be easily moved aside to uncover the crotch opening 2 for evacuation purposes.

5 Having thus described my invention what I claim as new and desire to secure by Letters Patent is:

1. A garment comprising a pair of bloomers having an opening in the crotch thereof; a separate strip arranged to cover said opening and having the ends only thereof secured to the front and rear portions of said garment whereby the intermediate portion of said strip may be isolated from other portions of said garment and washed separately therefrom; and means for imparting sufficient rigidity laterally to said strip to tend to prevent creasing and folding thereof whereby said strip may be pre-

vented from entering the inter-gluteal fold 20 of a wearer.

2. A garment comprising a pair of bloomers having an opening in the crotch thereof; a separate strip arranged to cover said opening and having the ends only thereof secured to the front and rear portions of said garment whereby the intermediate portion of said strip may be separated from said garment and washed separately therefrom; and lateral tapes secured to a portion of 30 said strip to impart sufficient rigidity thereto whereby the formation and entrance of longitudinal folds of said strip into the inter-gluteal fold of the wearer may be prevented. 35

In witness whereof I hereunto set my signature.

HATTIE MYRA WALSH.
